DESIGN FOR A COMBINATION TIE CLASP AND PENKNIFE OR SIMILAR ARTICLE

Arthur C. Braun, Maplewood, N. J.

Application September 24, 1940, Serial No. 95,333

Term of patent 3½ years

To all whom it may concern:

Be it known that I, Arthur C. Braun, a citizen of the United States and a resident of Maplewood, in the county of Essex and State of New Jersey, have invented a new, original, and ornamental Design for a Combination Tie Clasp and Penknife or Similar Article, of which the following is a specification, reference being had to the accompanying drawing, forming part thereof.

I claim:

The ornamental design for a combination tie clasp and penknife or similar article, as shown.

ARTHUR C. BRAUN.
